(57) **CLAIM**

The ornamental design for a patella cup protector, as shown and described.

DESCRIPTION

FIG. 1 is a front perspective view of the patella cup protector of the present invention showing our new design with the phantom lines depicting solely environmental structure and forming no part of the claimed design, it being furthermore understood that the straight, combination dashed and broken lines are for the purpose of showing the alignment of the patella cup protector onto the environmental structure, these lines also form no part of the claimed design;

FIG. 2 is a top plan view thereof;

FIG. 3 is a front elevational view thereof;

FIG. 4 is a left side elevational view thereof;

FIG. 5 is right side elevational view thereof;

FIG. 6 is a rear elevational view thereof; and,

FIG. 7 is a bottom plan view thereof.
